UNITED STATES PATENT OFFICE

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed July 31, 1923, Serial No. 654,875. Renewed March 27, 1930.

This invention comprehends improvements of general utility in the coking retort oven art; and also comprehends certain improvements especially applicable to coking 5 retort ovens of the Koppers regenerative type.

Important characteristics of the invention are: A construction of the regenerator ducts, flame flues, and horizontal flues that permits 10 the employment of more than one horizontal flue in each heating wall, instead of the known single horizontal flue which extends from end to end of the heating wall. In a heating wall provided with a plurality of 15 separate horizontal flues, each horizontal flue need communicate with only part, in the present instance only about one-half, of the total number of flame flues. By this construction there is brought about a proportionate reduction in the volume of flow which must be maintained through the horizontal flue and a resultant decrease in the size of the horizontal flue. This reduction in size of the 20 horizontal flues has an important advantage 25 that it enables a considerable thickening and strengthening of the walls of the oven structure in the region of the horizontal flues. Moreover, the improved flue construction permits an increase in the height of the upper 30 flame flues, with a corresponding increase 35 in the height of the coking chambers so that the latter may be made narrower in width, a development greatly facilitating the coking of high volatile coals, and yet the increased 40 volume of combustion products is taken care 45 of, without making it necessary to enlarge the horizontal flue dimensions to sizes inconsistent with adequate strength of the wall construction in the horizontal flue region.

The flue construction of the invention is furthermore of great importance in oven batteries fired with extraneously derived gas, such as producer gas, which results in an increased volume of combustion products, for 45 the reason that adequate flue spaces must be provided to collect and feed to the down-flow operating flame flues this increased volume. The invention provides adequate accommodation to such increased volume of 50 combustion products without introducing an

element of weakness into the wall structure.

In addition to the objects recited above, the invention comprehends a novel regenerator construction and system of flow therethrough and through the flues, promoting 55 uniformity of distribution, and has for other objects such other improvements or advantages in construction or operation as are found to obtain in the structures and devices hereinafter described or claimed.

In the accompanying drawings, forming a part of this specification, and showing, for purposes of exemplification, a preferred form and manner in which the invention may be embodied and practiced, but without limiting 60 the claimed invention to such illustrative instance or instances:

Figure 1 is a crosswise vertical section through a coke oven battery embodying features above specified and equipped with the 70 improvements of the present invention, the view being taken longitudinally through a heating wall and a pair of connected regenerators in planes indicated by the line A—A of Fig. 2;

Figure 2 is a composite vertical sectional elevation taken longitudinally of a coke oven battery, in planes indicated by the lines B—B and C—C of Fig. 1;

Figure 3 is horizontal section taken in the 80 plane indicated by the line D—D of Fig. 2;

Figure 4 is another horizontal section taken in the plane indicated by the line E—E of Fig. 2.

In the embodiment illustrated in the drawings, the invention is incorporated in a combination coke oven battery, i. e., a battery having provision for being fired alternatively with an extraneously derived, relatively lean gas, such as producer gas, or with a relatively 85 rich gas, such as coke oven gas. For convenience, the present description will be confined to the present illustrated embodiment of the invention in such a combination oven battery; certain features of the invention 90 may be applied to other structures, for example, to ordinary so-called "coke ovens" fired with coke oven gas, or ordinary so-called "gas ovens," fired with producer gas; hence, 95 the invention is not confined in its scope, ex- 100

cept as hereinafter claimed, to the combination oven, nor to the specific use and specific embodiment herein described as an illustrative example.

5 The by-product coke oven battery shown in the drawings includes the structural feature of a plurality of crosswise elongated spaced heating walls 11, 11, which provide intermediate crosswise elongated coking chambers or retorts 12, 12 of the horizontal chamber oven type. Supporting walls 13, 13 extend crosswise of the battery and, according to the present embodiment of the invention, are located both beneath the heating walls 11 and 10 the coking chambers 12. These supporting walls collectively form the main support for 15 the entire superstructure of the battery and are themselves supported upon a flat mat or platform which constitutes the sub-foundation 20 upon which the entire battery rests.

The coal to be coked is charged into the coking chambers 12 through charging holes 14 located in the top 15 of the battery and positioned directly above the respective coking 25 chambers as shown in Fig. 2. These charging holes 14 are equipped with the usual removable covers for closing the tops of the coking chambers during the coking or distilling of the coal. The evolved gases and 30 distillation products are discharged from the tops of the respective coking chambers 7 through the usual gas outlets (not shown) and thence through ascension pipes (not shown) into the usual gas collecting main, through which the gases and distillation products pass to the by-product recovery apparatus.

Heat for coking the charges of coal in the several coking chambers 12 is derived from 40 the crosswise heating walls 11, which form the side walls of the coking chambers. Each heating wall 11 is provided with vertical flame or combustion flues 17.

Referring more particularly to Fig. 1, the 45 flame flues 17 of each heating wall are disposed into the two main groups M and N corresponding to the respective horizontal flues with which said groups communicate. Each main group of flame flues, M or N, is divided 50 into sub-groups of flues O and P, in accordance with the direction of flow of the heating gases through the flues. When the flame flues of the two groups O of each heating wall are operating for inflow, i. e. combustion, the 55 flame flues of the two groups P are operating for outflow, i. e. discharge of the combustion products. As shown in Fig. 1, the two groups O of flame flues may be termed outside groups 60 since they are disposed nearer to the side walls of the battery structure, whereas the two groups P of flame flues may be termed inside groups, being located in the interior of the battery structure. It is preferable to have 65 both outside groups of flues operate concurrently for flow in one direction, for example,

for inflow, while both inside groups P are operating concurrently for flow in the opposite direction, i. e. for outflow. However, the battery structure permits an outside and an inside group to operate concurrently for inflow 70 while the other outside and inside groups are operating for outflow.

The crosswise regenerators 18 of the retort oven or battery are located at a lower level than the heating walls 11 and coking chambers 12, and, in the present instance, extend in parallelism between the supporting walls 13. Located in the middle lengthwise vertical plane of the battery, is a vertical partition 19, as shown in Fig. 1, which extends from the mat of the battery to the bottom of the outlying coking chamber or heating wall and interconnects the supporting walls 13. The regenerators, which are respectively located on opposite sides of the battery, extend inwardly to the partition 19 and are separated thereby, as clearly shown in Fig. 1. This arrangement permits control from opposite sides of the battery of the flow through the regenerators, thereby assisting the novel flue arrangement in promoting uniformity of distribution. Each regenerator 18 is a chamber containing the checker brick 20, with a distributing sole channel 21 underneath and communicating with the checker brick. During alternate outflow reversal periods, the regenerators are heated by the hot combustion products from the flame flues and, during the other inflow reversal periods, the heat so stored in the regenerators is imparted to the medium, which passes through the regenerators into the flame flues. According to the invention, the several regenerators, taken longitudinally of the battery, are grouped into the alternate pairs R corresponding with and operating for flow in the same direction as an outside group of flues O of one heating wall and an inside group of flues P of one of the adjacent heating walls, and into intermediate pairs S of regenerators corresponding with and operating for flow in the same direction as an inside group of flues P of one heating wall and an outside group of flues O of one of the adjacent heating walls. With this construction, each regenerator or pair 100 of regenerators which operate similarly as to flow is connected with an outside group of flues O of one heating wall and an inside group of flues P of one of the adjacent heating walls. The heating walls are grouped into the alternate walls T and intermediate walls U, see Fig. 2. When the outside groups of flues O of the alternate heating walls T are operating for inflow, the outside groups O of the intermediate heating walls U are operating for outflow. At this time the inside groups of flues P of the alternate walls T would be operating for outflow and the inside groups P of the intermediate walls U would be operating for inflow. On reversal 110

of the battery, the inflow regenerators and corresponding groups of flues are switched to outflow, and the outflow groups of flues and regenerators are switched to inflow operation.

Each regenerator is provided with two series of ducts 23 and 24 of which the outside series of ducts leads to and connects the regenerator with the corresponding outside group of flame flues O of one heating wall and the inside series of ducts 24 leads to and connects the regenerator with the inside group of flues P of an adjacent heating wall. This novel arrangement of the duct connections between the regenerators and the flues of the heating walls permits each main group M or N of flame flues, with its communicably connected regenerators, to be operated according to the regenerative reversal principle independently of the other main group of flues of the same heating wall, and thus permits the employment of as many horizontal or bus flues as there are main groups of combustion flues in any heating wall of the battery. Moreover, the hereinbefore described duct connections between regenerators and flame flues permit operation of the battery alternatively with a relatively rich gas, such as coke oven gas, or with a preheated relatively lean extraneously derived gas, such as producer gas, according to the combination oven principle.

Each flame flue 17 of each heating wall has at its top a port or opening 25 for draft and the passage of combustion products or waste gases. These ports 25 connect the flame flues 17 with the horizontal or bus flues 26 located in the heating walls above the flame flues and corresponding to the main groups M and N of the several heating walls. There are in each heating wall, according to the present embodiment of the invention, two of these horizontal flues 25 arranged in end-wise relation to each other and respectively serving approximately one-half of the flame flues of the heating wall. It should be noted that a sub-group O or P of flame flues comprises approximately one-half of the main group, or about one-fourth of the total number of flues of the heating wall. On account of the division of the flow above the flame flues into a plurality of horizontal flues 26, the individual horizontal flues are not required to be of so great capacity as that necessary in the known practice employing the single horizontal flue. Consequently, the cross-sectional area of each horizontal flue 25 may be materially reduced proportionately with the reduced number of connected flame flues, with the result that the thickness and strength of the heating walls are substantially increased in the region of the horizontal flues. Moreover, because of the fact that the necessity for redistribution of the flow between the horizontal flues and flame

flues is confined to a reduced number of flame flues, in the present instance only about one-half of the total number of flame flues in the heating wall, uniformity in distribution of the flow between flame flues and regenerators throughout the battery structure is greatly promoted.

Extending crosswise of the battery in the structure above alternate supporting walls 13 and located beneath the heating walls 11, 75 is a pair of coke oven or relatively rich gas supply channels 29 and 30. These pairs of channels 29 and 30 respectively extend inwardly from the opposite sides of the battery, and the channels 29 serve the flues of 80 the outside groups O and the channels 30 the flues of the inside groups P. These channels respectively communicate by gas ducts 31 with their corresponding flame flues. Within the several ducts 31 are located the 85 usual nozzles 32. The supply of coke oven gas to the respective channels 29 and 30 may be derived from coke oven gas mains of the usual type which extend longitudinally at the opposite sides of the battery. Suitable 90 mechanism is provided for controlling the supply of fuel gas to the channels 29 and 30, as required by battery operation.

When firing the battery with extraneously derived lean gas, such as producer gas, all 95 the channels 29 and 30 are cut off from the coke oven gas supply. Assuming that the alternate pairs R of regenerators and that the outside groups O of the alternate heating walls T and the inside groups P of the intermediate heating walls U are operating 100 for inflow, and that the intermediate pairs S of regenerators and the inside groups P of the alternate heating walls T and outside groups O of the intermediate heating walls 105 U are operating for outflow, a supply of producer gas is permitted to flow into one regenerator G of each alternate pair R. Passing through said regenerators G, the producer gas is preheated before being delivered into the burning flame flues. During 110 the inflow of producer gas through such regenerators G, inflow of air is maintained in the other regenerators A of the alternate pairs R. The air passing upwardly through the regenerators A finally enters the burning flame flues to support the combustion of the producer gas that is delivered thereto by the regenerators G. During the inflow through the regenerators R and the connected flame 115 flues, the waste gas from the horizontal flues 26 and the outflow operating groups of flues is flowing through both regenerators of the connected intermediate pairs S, so that said regenerators S operate as waste gas regenerators W. On reversal of the flow, the inflow operating regenerators become outflow regenerators and concurrently the outflow operating regenerators become inflow 120 regenerators. 125

In operating the battery with coke oven gas, the supply of producer gas to regenerators G is shut off and air is permitted to flow into such regenerators in place of the producer gas. During coke oven gas operation, a supply of coke oven gas is maintained in such of the channels 29 and 30 which feed the upburning flues. The reversing mechanism is operated at each reversal to place all of the inflow operating regenerators in communication with the outer air and concurrently all of the outflow operating regenerators in communication with the exhaust.

15 The invention as hereinabove set forth is embodied in a particular form of construction, but may be variously embodied within the scope of the claims hereinafter made.

I claim:

20 1. In a coke oven battery, in combination: a plurality of coking chambers; heating walls contiguous to such coking chambers and respectively comprising vertical combustion flues; a pair of horizontal flues in each heating wall and respectively connecting approximately one-half of the combustion flues of their respective heating walls, each group of combustion flues so connected by horizontal flues being constituted of an outside sub-group for flow in one direction and an inside sub-group for flow in the opposite direction; and crosswise regenerators grouped in pairs in respect of the gas flow, with the alternate pairs operating for inflow while the intermediate pairs operate for outflow, each regenerator being connected by duct means with an outside sub-group of flues of one heating wall and an inside sub-group of flues of one of the next adjacent heating walls, and each sub-group of said flues having flow connection with a pair of regenerators through which flow may be maintained in the same direction in one as in the other thereof, the inflow regenerators being jointly operable for conveying air to the flues or separately operable for conveying air and an extraneously derived gas; substantially as specified.

25 2. In a coke oven battery, in combination: a plurality of coking chambers; heating walls contiguous to such coking chambers and respectively comprising vertical combustion flues; a pair of horizontal flues in each heating wall and respectively connecting approximately one-half of the combustion flues of their respective heating walls, each group of combustion flues so connected by horizontal flues being constituted of an outside sub-group for flow in one direction and an inside sub-group for flow in the opposite direction; and crosswise regenerators grouped in pairs in respect of the gas flow, with the alternate pairs operating for inflow while the intermediate pairs operate for outflow, each regenerator being connected by duct means

with an outside sub-group of flues of one heating wall and an inside sub-group of flues of one of the next adjacent heating walls, and each sub-group of said flues having flow connection with a pair of regenerators through which flow may be maintained in the same direction in one as in the other thereof; substantially as specified.

3. In a coke oven battery, in combination: a plurality of coking chambers; heating walls contiguous to such coking chambers and respectively comprising vertical combustion flues; a pair of horizontal flues in each heating wall and respectively connecting approximately one-half of the combustion flues of their respective heating walls, each group of combustion flues so connected by horizontal flues being constituted of an outside sub-group for flow in one direction and an inside sub-group for flow in the opposite direction; and regenerators grouped in pairs in respect of the gas flow, with the alternate pairs operating for inflow while the intermediate pairs operate for outflow, each regenerator being connected by duct means with an outside sub-group of flues of one heating wall and an inside sub-group of flues of one of the next adjacent heating walls, and each sub-group of said flues having flow connection with a pair of regenerators through which flow may be maintained in the same direction in one as in the other thereof, the inflow regenerators being jointly operable for conveying air to the flues or separately operable for conveying air and an extraneously derived gas; substantially as specified.

4. In a coke oven battery, in combination: a plurality of coking chambers; heating walls contiguous to such coking chambers and respectively comprising vertical combustion flues; a pair of horizontal flues in each heating wall and respectively connecting approximately one-half of the combustion flues of their respective heating walls, each group of combustion flues so connected by horizontal flues being constituted of an outside sub-group for flow in one direction and an inside sub-group for flow in the opposite direction; and regenerators grouped in pairs in respect of the gas flow, with the alternate pairs operating for inflow while the intermediate pairs operate for outflow, each regenerator being connected by duct means with an outside sub-group of flues of one heating wall and an inside sub-group of flues of one of the next adjacent heating walls, and each sub-group of said flues having flow connection with a pair of regenerators through which flow may be maintained in the same direction in one as in the other thereof; substantially as specified.

5. In a coke oven battery, in combination: a plurality of coking chambers; heating walls contiguous to such coking chambers and respectively comprising vertical combustion flues disposed into main groups; a plu-

rality of horizontal flues in each heating wall and respectively connecting the combustion flues of each of said main groups, each group of combustion flues so connected by horizontal flues being constituted of an outside sub-group for flow in one direction and an inside sub-group for flow in the opposite direction; and crosswise regenerators grouped in pair in respect of the glass flow, with the alternate pairs operating for inflow while the intermediate pairs operate for outflow, each regenerator being connected by duct means with an outside sub-group of flues of one heating wall and an inside sub-group of flues of one of the next adjacent heating walls, and each sub-group of said flues having flow connection with a pair of regenerators through which flow may be maintained in the same direction in one as in the other thereof, the inflow regenerators being jointly operable for conveying air to the flues or separately operable for conveying air and an extraneously derived gas; substantially as specified.

6. In a coke oven battery, in combination: a plurality of coking chambers; heating walls contiguous to such coking chambers and respectively comprising vertical combustion flues disposed into main groups; a plurality of horizontal flues in each heating wall and respectively connecting the combustion flues of each of said main groups, each group of combustion flues so connected by horizontal flues being constituted of an outside sub-group for flow in one direction and an inside sub-group for flow in the opposite direction; and crosswise regenerators grouped in pairs in respect of the gas flow, with the alternate pairs operating for inflow while the intermediate pairs operate for outflow, each regenerator being connected by duct means with an outside sub-group of flues of one heating wall and an inside sub-group of flues of one of the next adjacent heating walls, and each sub-group of said flues having flow connection with a pair of regenerators through which flow may be maintained in the same direction in one as in the other thereof; substantially as specified.

7. In a coke oven battery, in combination: a plurality of coking chambers; heating walls contiguous to such coking chambers and respectively comprising vertical combustion flues disposed into main groups; a plurality of horizontal flues in each heating wall and respectively connecting the combustion flues of each of said main groups, each group of combustion flues so connected by horizontal flues being constituted of an outside sub-group for flow in one direction and an inside sub-group for flow in the opposite direction; and regenerators grouped in pairs in respect of the gas flow, with the alternate pairs operating for inflow while the intermediate pairs operate for outflow,

each regenerator being connected by duct means with an outside sub-group of flues of one heating wall and an inside sub-group of flues of one of the next adjacent heating walls, and each sub-group of said flues having flow connection with a pair of regenerators through which flow may be maintained in the same direction in one as in the other thereof; substantially as specified.

8. In a coke oven battery, in combination: a plurality of coking chambers; heating walls contiguous to such coking chambers and respectively comprising vertical combustion flues; a pair of horizontal flues in each heating wall and respectively connecting approximately one-half of the combustion flues of their respective heating walls, each group of combustion flues so connected by horizontal flues being constituted of an outside sub-group for flow in one direction and an inside sub-group for flow in the opposite direction; and crosswise regenerators having inflow regenerators alternating with outflow regenerators, each regenerator being connected by duct means with an outside sub-group of flues of one heating wall and an inside sub-group of flues of one of the next adjacent heating walls; substantially as specified.

9. A coke oven battery having side by side coke chambers with intermediate heating walls, characterized by heating walls individually comprising both inflow groups and outflow groups of combustion flues, with bus flues connecting inflow groups with outflow groups, in combination with pairs of regenerators of which both regenerators of a pair are communicably connected in parallel with the same combustion flues, each such pair of regenerators being individual to a group of flues of each heating wall on opposite sides of an intervening coking chamber connected for flow in the same direction; substantially as specified.

10. A coke oven battery having side by side coking chambers with intermediate heating walls, characterized by heating walls individually having at least two groups of inflow flues and at least two groups of outflow flues, with a bus flue connecting an inflow group with an outflow group, combined with pairs of inflow and outflow regenerators, each such pair of regenerators being connected with a similarly operating group of flues of each of the two heating walls on the opposite sides of an intervening coking chamber; substantially as specified.

11. In a coke oven battery, in combination: a plurality of coking chambers; heating walls contiguous to such coking chambers and respectively comprising combustion flues in groups; bus flues in the heating walls respectively connecting the combustion flues of each of said groups, each group of combustion flues so connected by a bus

flue being constituted of a sub-group for inflow in one direction and another sub-group for outflow in the opposite direction, the inflow and outflow sub-groups in adjacent heating walls being staggered with respect to each other; substantially as specified.
